UNITED STATES PATENT OFFICE.

LOUIS G. SMITH, OF BROCKTON, MASSACHUSETTS, ASSIGNOR TO UNITED SHOE MACHINERY CORPORATION, OF PATERSON, NEW JERSEY, A CORPORATION OF NEW JERSEY.

SOLE-ROUNDING MACHINE.

1,331,789.

Specification of Letters Patent. Patented Feb. 24, 1920.

Application filed March 19, 1919. Serial No. 283,475.

To all whom it may concern:

Be it known that I, LOUIS G. SMITH, a citizen of the United States, residing at Brockton, in the county of Plymouth and 5 State of Massachusetts, have invented certain new and useful Improvements in Sole-Rounding Machines; and I do hereby declare the following to be a full, clear, and exact description of the invention, such as 10 will enable others skilled in the art to which it appertains to make and use the same.

The invention relates to machines for rounding or rounding and channeling the soles of shoes.

15 The invention is intended primarily to improve the operation of the crease and forepart guides of the machine of Patent No. 1,030,606, June 25, 1912, in rounding shoes in which the forepart of the sole is trimmed 20 closer than the shank. The mechanism which is utilized in this machine for causing the crease guide to rise as the forepart guide is moved into active position when trimming closer about the forepart than in 25 the shank, comprises a roll mounted on the forepart guide lever near its fulcrum, and arranged to be engaged by a cam plate on the crease guide lever. With this construction the movement of the roll, due to the 30 movement of the forepart guide from its inactive to its active position, is necessarily slight, and in order to secure such movement of the crease guide as is usually required, the plate on the crease guide must be shaped 35 to allow the crease guide to move upward during substantially the entire downward movement of the forepart guide. This is undesirable, and frequently results in imperfect work in passing from the shank to the 40 forepart. The present invention provides a mechanism which may be readily applied to the above machine to delay the upward movement of the crease guide until the forepart guide has nearly reached the shoe, and 45 then to permit it to quickly rise as the control of the shoe passes from the crease guide to the forepart guide, thus securing the proper timing of the upward movement of the crease guide requisite for uniformly ac- 50 curate work at the juncture of the shank and forepart when trimming closer about the forepart than in the shank.

The preferred form of the invention is shown in the drawings, in which Figure 1 is 55 a side view of so much of the machine of the

above patent as is necessary to illustrate the application of the present invention thereto, and Fig. 2 is a similar view showing the parts in a different position.

The machine shown is provided with a reciprocating trimming knife 2, a channel knife 4 carried in the channel knife block 6, a feed jaw 8, a crease guide 10, and a forepart guide 12. The forepart guide is carried on the forward end of the forepart guide 60 lever 14, which is moved into and out of active position through a rock shaft 16 connected with the lever through an arm 18 and link 20, and connected with an operating treadle through an arm 22 and treadle rod 70 24. The crease guide 10 is secured at the forward end of a crease guide lever 26 which is held in engagement with the devices which determine its vertical position and control its vertical movements by the usual 75 spring (not shown).

The mechanism for controlling the vertical movements of the crease guide to trim closer about the forepart than through the shank comprises a fixed abutment 28 overlying the crease guide lever, and a controller bar 30 interposed between the abutment and a wear plate 32 on the lever, and so connected with the mechanism for moving the forepart guide into and out of active position that it will lie between the abutment and wear plate when the forepart guide is in inactive position, and will be withdrawn from between the abutment and wear plate 85 during the movement of the forepart guide 90 from inactive to active position. The abutment 28 is preferably in the form of a roll, and the abutment roll shown and described in the above patent may be conveniently utilized as the abutment of the present mechanism in applying the invention to the machine of that patent. In such case the abutment roll is mounted in a plate 34 secured to the side of the forepart guide lever, and this plate should be adjusted to bring 95 the roll substantially in line with the fulcrum of the lever, so that its position will not be materially affected by the movement of the forepart guide into and out of active position. As shown, the rear end of the controller bar is pivotally connected to an arm 36 which is adjustably secured to the rock shaft 16 through which the forepart guide is moved into and out of active position. 105 110 115

When the forepart guide is in its raised inactive position the controller bar lies between the abutment roll and the plate on the crease guide lever and supports the lever 5 during the operation through the shank. When the forepart guide is moved down into active position the bar is withdrawn, and as its end passes from between the roll and plate, the crease guide quickly rises 10 to meet the forepart guide lever, after which it is free to accompany the forepart guide in its movements as usual. The parts may be so adjusted that the end of the controller bar does not pass from between the roll and 15 plate until the forepart guide has nearly reached its active position in engagement with the shoe, thus delaying the upward movement of the crease guide until the forepart guide is in position to take over the 20 control of the shoe, and insuring the accurate and proper control of the shoe in passing from the shank to the forepart. The plate 32 may be adjusted vertically to determine the projection of the sole through 25 the shank, and its adjustment may be determined by a stop screw 38, the head of which engages the lower end of the plate. The plate may be secured in position by a clamping screw 40. The upper end of the 30 plate may be more or less cam shape to co-operate with the end of the controller bar and the periphery of the abutment roll in controlling the upward movement of the crease guide as the end of the bar withdraws 35 from between the roll and plate, and to facilitate the entrance of the end of the bar between the roll and plate when the forepart guide is returned to inactive position in passing from the forepart to the 40 shank.

While it is preferred to employ the specific construction and arrangement of parts in applying the invention to the machine of the above patent, since this construction and arrangement may be readily incorporated in existing machines, it will be understood that the invention is not limited in its application to this machine, or to the specific construction and arrangement of parts 45 shown and described.

What is claimed is:—

1. A sole rounding machine, having, in combination, a forepart guide, a crease guide lever, a crease guide at the forward 55 end of the lever, an abutment overlying the lever, a controller bar between the abutment and lever, and mechanism for withdrawing the bar as the forepart guide is brought into active position.
- 60 2. A sole rounding machine, having, in combination, a forepart guide, a crease

guide lever, a crease guide at the forward end of the lever, an abutment overlying the lever between its fulcrum and the crease guide, a controller bar between the 65 abutment and lever, and connections for withdrawing the bar in moving the forepart guide into active position.

3. A sole rounding machine, having, in combination, a forepart guide, a crease 70 guide lever, a crease guide at the forward end of the lever, an abutment overlying the lever, a bar between the abutment and lever, and connections for retracting the bar during the movement of the forepart guide 75 into active position constructed to withdraw the end of the bar from between the lever and abutment as the forepart guide reaches active position.

4. A sole rounding machine, having, in combination, a forepart guide, a crease 80 guide lever, a crease guide at the forward end of the lever, a vertically adjustable plate on the lever, an abutment overlying the plate, a controller bar arranged to lie 85 between the abutment and plate when the forepart guide is out of active position, and means for withdrawing the end of the bar from between the abutment and plate during the final movement of the forepart 90 guide into active position.

5. A sole rounding machine, having, in combination, a forepart guide, a rock shaft connected to move the guide into active position, a crease guide lever, a crease guide 95 at the forward end of the lever, an abutment overlying the lever, a bar lying between the abutment and lever, and an arm on the forepart guide rock shaft to which the rear end of the bar is connected. 100

6. A sole rounding machine, having, in combination, a forepart guide lever, a crease guide lever, a roll secured to the forepart guide lever substantially in line with its fulcrum, a plate on the crease guide 105 lever underlying the roll, and a bar arranged to be advanced and retracted between the roll and plate upon movement of the forepart guide out of and into active position. 110

7. A sole rounding machine, having, in combination, a forepart guide normally held in raised inactive position, a creased guide for guiding the shoe while operating through the shank, means for moving the forepart guide device into active position, and mechanism for retaining the crease guide in normal position until the forepart guide nearly reaches the shoe and then causing it to quickly rise to meet the forepart guide. 115 120
